site the threaded end 32. Rod 31 is passed through a bore which extends longitudinally through base piece 10. Base piece 11 is provided with a threaded bore 34 which extends longitudinally therein. The threading 32 on rod 31 is similar to the threading in the bore 34 and rod 31 may be thread-driven in bore 34 to accomplish the adjustment of base pieces 10 and 11, and to hold the base pieces in their adjusted position with the abrasive wheels 15 and 20 in the desired contacting relationship.

As viewed from above, the abrasive wheels 15 and 20 form a wide V. When the device is being used, I recommend that the knife blade be moved from the point towards the wide end of this V. The knife should be drawn or pushed in one direction only. When the knife is drawn in the recommended direction, both wheels will rotate upwardly as viewed from the point of contact 25. The passage of the knife between the wheels at the point 25 will serve both to sharpen the cutting edge of the knife and at the same time remove some of the thick heel of the knife.

If desired, a bevelled edge such as 26 may be provided on each side of each wheel 15 and 20, so that if the bevel at one side is given excessive wear, the wheels may be removed from their supporting elements 12 and 13 and reversed so that a new bevelled edge is brought into play in the case of each wheel. Although beveling of the edges is presently preferred, I do not regard it as essential to the invention.

What I claim as my invention is:

1. A knife sharpener comprising a two-piece base unit in which the major planes of the two base pieces are co-planar; a wheel-supporting element rigidly secured to each base piece; and an abrasive wheel rotatably mounted by each wheel-supporting element; said abrasive wheels being disposed with their peripheries in contact, with their axes of rotation intersecting at an acute angle, and with their planes of rotation forming an acute angle with the major plane of the base, whereby said wheels will rotate as a knife blade is drawn therebetween at their point of contact; said two base pieces being so con-

nected that they are held in the same major plane but may be adjusted toward one another to maintain contact between the abrasive wheels as the latter wear; and means for locking the two base pieces in their adjusted positions.

2. A knife sharpener as defined in claim 1, in which said abrasive wheels are similar cylinders and the cylindrical edge of each wheel is bevelled along the line where it meets one of the side faces of the wheel, the point of contact of the two wheels being between the two bevelled edges.

3. A knife sharpener as defined in claim 1, in which the means for locking the two base pieces in their adjusted position comprises a rod having a threaded end and a bore in each of said base pieces, one of said bores being threaded, said rod being passed through the bore in one of the base pieces and threadedly engaged in the threaded bore in the other base piece.

4. A knife sharpener as defined in claim 1, in which said two base pieces are connected by at least two bars, each of which extends from one of the base pieces in a plane which is parallel to the major plane of the base pieces and enters a bore in the opposite base piece, the bores also being parallel to the major plane of the base.

5. A knife sharpener as defined in claim 4, in which the means for locking the two base pieces in their adjusted position comprises a rod having a threaded end and a bore in each of said base pieces, one of said bores being threaded, said rod being passed through the bore in one of the base pieces and threadedly engaged in the threaded bore in the other base piece.
